UNITED STATES PATENT OFFICE

158,802

AUTOMOTIVE GRILL GUARD OR SIMILAR ARTICLE

Max J. Rubel, Chicago, Ill., assignor to Erie Manufacturing Co., Inc., Chicago, Ill., a corporation of Illinois

Application December 13, 1947, Serial No. 143,136

Term of patent 3½ years

(Cl. D14—6)

To all whom it may concern:

Be it known that I, Max J. Rubel, a citizen of the United States, residing at Chicago, in the county of Cook and State of Illinois, have invented a new, original, and ornamental Design for an Automotive Grill Guard or Similar Article, of which the following is a specification, reference being had to the accompanying drawing, forming a part thereof.

Fig. 2 shows a plan view of the article;

Fig. 3 is a cross-sectional view on the line 3—3 of Fig. 2, and

Fig. 4 is a cross-sectional view on the line 4—4 of Fig. 2.

The dotted lines shown in Fig. 1 are for illustrative purposes only.

I claim:

The ornamental design for an automotive grill guard or similar article, substantially as shown and described.

MAX J. RUBEL.
